UNITED STATES PATENT OFFICE.

JOHN A. CARLSTROM, OF NEW YORK, N. Y., ASSIGNOR TO THE JOHN J. MITCHELL CO., OF NEW YORK, N. Y.

TAILOR'S SQUARE.

No. 918,279.

Specification of Letters Patent.

Patented April 13, 1909.

Application filed May 2, 1908. Serial No. 430,472.

To all whom it may concern:

Be it known that I, JOHN A. CARLSTROM, a citizen of the United States, and a resident of the city of New York, Flushing, borough 5 of Queens, in the county of Queens and State of New York, have invented a new and Improved Tailor's Square, of which the following is a full, clear, and exact description.

10 The invention relates to drafting and measuring instruments, and its object is to provide a new and improved tailor's square, arranged for conveniently obtaining any division of any breast size in drafting garments, 15 without requiring calculation on the part of the tailor, and thus reducing the making of mistakes and errors in drafting, to a minimum.

20 The invention consists of novel features and parts and combinations of the same, which will be more fully described hereinafter and then pointed out in the claims.

25 A practical embodiment of the invention is represented in the accompanying drawings forming a part of this specification, in which similar characters of reference indicate corresponding parts in both views.

30 Figure 1 is a plan view of the improvement; Fig. 2 is an enlarged plan view of part of the same; Fig. 3 is a diagram representing a portion of the lines for laying off a coat from back center to front center.

35 The tailors' squares, as heretofore constructed, were arranged for obtaining fractions of parts of breast sizes up to 48 inches only, and hence it was impossible with the use of such a square to obtain the divisions of breast sizes for persons of a larger breast circumference than 48 inches. In such cases 40 the tailor had to resort to considerable calculation in order to obtain the desired result. To overcome this difficulty and to permit the use of the square for obtaining divisions of breast sizes up to the largest size 45 met with in practice, say up to 96 inches, is the object of the invention presently to be described in detail.

50 The short and long arms or legs A and A' of the tailor's square shown in Figs. 1 and 2 are provided along the inner margins with the usual inch scales B and B', and along the outer margins are arranged the ordinary breast-size scales C, C', expressed in fractions of inches as units. Thus the scales C 5 on the short arm A have as units halves,

4ths, 8ths, 16ths, and 32ds of an inch, while the scales C' on the long arm A' have as units 2 thirds, 3ds, 6ths, 12ths, and 24ths of an inch. Each of these breast size scales has its principal divisions numbered from 12 60 to 24, and the numeral designating the division is one-half of the whole breast size of which the length from the end of the square to the division bearing the numeral is the proper fraction. Thus 22 in any one of the 65 scales C and C' represent one-half of the whole breast measuring 44 inches. Adjacent to the scales C, C' and between the latter and the scales B, B' are arranged the supplementary scales D, D', representing 70 fractions of the half breast size and forming continuations of the corresponding scales C, C'. The supplementary scales D, D' are laid out and marked in whole breast sizes instead of in half breast sizes, as above mentioned relative to scales C, C'. 75

By reference to Figs. 1 and 2, it will be seen that the scale D' for sixths of the half breast measure and which is arranged on the long arm A', is continued from 48" up to 80 94" along the scale C' for thirds of the half breast measure, so that the sixths of half breast measures from 12 to 96 can be obtained from the use of this scale. In a like manner the supplementary scale D for the 85 eightths of the half breast measure on the short arm A, is continued along the scale C for fourths of the half breast measure, and the supplementary scale D for sixteenths is continued adjacent to the scale for eightths 90 as indicated in Figs. 1 and 2. But each of said scales C and D for a particular fraction of the half breast measure include all fractions from the smallest size to the largest size met with in practice. 95

It will be understood that in laying off a garment, the breast measure is the basis, and the remaining dimensions are proportioned to the special breast measurement. In laying off a garment, the commencing line is along 100 the center of the back, and the basis for the pattern is a line along the said center, in length one-third of the half breast measure. The scales C, C' are so arranged that the numerals thereon will be opposite the numerals on the 105 scales B, B', which correspond to the third of the numeral on the scales C, C', as for instance, in Fig. 2, the numeral 24 on the scale C' corresponds with the position of the numeral 4 in the scale of sixths, 4 being one-sixth of 110

24. In the scale of 3rds, the numeral 6 on the scale B', corresponds to the position of the numeral 18 on the scale C', 6 being $\frac{1}{3}$ of 18. In laying off the garment, the basis as before stated is one-third of the half of the known breast measure, which in a 36 inch breast measure for instance, would be 6 inches. To this an arbitrary quantity is added to carry the length desired for the half length of the coat. This arbitrary quantity of course depends upon the fashion, and upon the relative height of the individual. From the line formed by the base, and the arbitrary quantity, the half garment (*i. e.*, halfwidth) is laid off, as the pattern is drafted for one side only. The line A—D in Fig. 3 is always one-twelfth of the half breast size, and the line D—E is an arbitrary addition depending as before stated upon the peculiarities of the individual, and of the fashion. The line E—F, is five-eighths of an inch also an arbitrary quantity. The line C—G is one-fourth of the half breast measure, and the line G—H is an arbitrary addition for the same reason stated for the lines A, D, and D—E. From H to I is one-eighth of the half breast measure. The remainder of the pattern is laid off in the same manner, certain portions of the lines being in one-thirds, one-fourths etc. of the breast measure, and other portions arbitrary, lengths, depending as previously stated upon the fashion prevailing and upon the peculiarities of the individual for whom the garment is designed. As before stated tailors' squares have been arranged up to 48 inches, but in order to obtain the proportionate measures for larger sizes, it was necessary to calculate such measurements, and afterward lay them off. The scales D, D' carry the calculations forward, thus dispensing with the necessity for calculation.

It will be observed, that the division lines on the scales D, D' corresponding to the breast sizes of the supplementary scale are arranged in alinement with the divisions marking the fractions of inches. As, for instance, the breast size 60 corresponds in position with the line marked 5 in the inch scale. One-half of 60 is 30, and one-third of 30 is 10, which is twice 5. This relation

will be found throughout the scales, that is 50 the numeral designating the division on the inch scale will correspond to a breast size whose half measure is three times twice the numeral. In laying off from the supplementary scale, instead of laying off a number of inches corresponding to the position of the breast size, double such number of inches as laid off. 55

In Fig. 3, the line A, B represents one-third of the half breast measure, and the line 60 B, C represents the arbitrary quantity added to compensate for differences, and the said line A, B is the base from which the other measurements are laid off.

Having thus described my invention, I 65 claim as new and desire to secure by Letters Patent:

1. A tailor's square having an arm provided on one edge with a scale of inches and fractions thereof, and on the other edge with 70 a scale of various fractions of usual half breast sizes, the divisions marking the half breast sizes, being arranged in alinement with the appropriate divisions of the other scale, and a supplementary scale intermediate the two scales, the divisions of the supplementary scale, being in alinement with divisions of the first scale corresponding to half the appropriate fraction. 75

2. A tailor's square having an arm provided with a scale of inches and fractions thereof, and with a scale of various fractions of usual half breast sizes, the divisions marking the half breast sizes, being arranged in alinement with the appropriate divisions of 85 the other scale, and a supplementary scale, the divisions of the supplementary scale being in alinement with divisions of the first scale corresponding to half the appropriate fraction. 90

In testimony whereof I have signed my name to this specification in the presence of two subscribing witnesses.

JOHN A. CARLSTROM.
